JOSEPH L. KALLUS, OF BROOKLYN, NEW YORK

DOLL

Application filed March 12, 1929. Serial No. 348,329.

My invention relates to dolls and more particularly to that type of dolls which includes a head movable or adjustable to different positions. Up to the present time the 5 necks of dolls of the indicated class have always been constructed as integral parts either of the heads or bodies thereof, and dolls constructed in this manner with adjustable heads are old and well known. 10 Such existing dolls include disadvantages with respect to the manufacture thereof, and also in connection with the assembling and operation of the parts, and in a comparatively short space of time develop defects 15 which destroy their characteristics as dolls with consequent loss of attractiveness to the children. The object of the present invention is to overcome these disadvantages by constructing the doll necks as separate units 20 or elements, independent of the heads or bodies, and then combining such separate necks with the heads and bodies in predetermined ways to form the completed dolls. Other more specific objects will appear from 25 the description hereinafter, and the features of novelty will be pointed out in the claim.

In the accompanying drawing, which illustrates several examples of the invention without defining its limits, Fig. 1 is an elevation 30 showing one type of doll embodying the novel features; Fig. 2 is a fragmentary section on an enlarged scale, of the head, neck and body of said doll; Fig. 3 is a view similar to Fig. 2 showing another form of the invention; Fig. 35 4 is an inverted end view of the neck member of the doll of Fig. 3; Fig. 5 is a fragmentary view, partly in section, illustrating still another form of the invention, and Fig. 6 is an enlarged fragmentary section of a doll head 40 showing a fastening means included in the novel arrangement.

The type of doll body and the construction and form thereof as to material and arrangement may be of any conventional type as this 45 forms no part of the present invention.

In Fig. 1 I have accordingly shown a doll comprising a body 10 having the usual arms 11 and legs 12. In the form illustrated, the body 10 is made of any suitable rigid material, such as bisque, wood pulp composition, 50 wood, papier mâché or the like, and generally is of hollow form. Similarly the head 13 may be of any customary type and construction, excepting as hereinafter pointed out, and may also be made of any suitable material such as hereinbefore pointed out.

In dolls of the class including a movable or adjustable head, as heretofore made, the neck comprises either an integral part of the body 10, or a correspondingly integral part of the 60 head 13, it being well known in the art to provide dolls in which the head is adjustable to different positions relatively to the body. The essence of the present invention consists in constructing the neck of the doll as a separate neck member independently of the body and head to thereby provide a doll construction possessing material advantages over existing type of dolls and including none of the disadvantages thereof.

In the form shown in Figs. 1 and 2, the neck consists of a member 14 of suitable material and of cylindrical form, the one end of which is rounded as indicated at 15 and fitted into a neck socket 16 with which the 70 head 13 is provided and the peripheral surface of which is bevelled or curved to fit the rounded end 15 of the neck member 14. The opposite end of the neck member 14 is approximately flat and extends into a neck 80 recess 17 formed in the upper part of the body 10, as shown in Fig. 2; the neck recess 17 includes an internal flange 18, which constitutes the bottom of said recess 17 upon which the neck member 14 rests. In the example now 85 being described, the neck member 14 is fixed or secured in the recess 17 in any convenient manner, as by gluing or cementing it in place so as to form a rigid continuation of the body 10, as clearly illustrated. Any suitable 90 means may be provided for maintaining the head 13 in movable connection with the neck member 14. As shown in Fig. 2, this means comprises a rod 19 connected with the head 13, preferably in the novel manner to be more 95 fully set forth hereinafter, and a spring 20 having its one end fastened to the free end of the rod 19 and its other end connected with a cross bar 21 located at the lower end of said neck member 14, preferably in a recess 22 100

with which the neck member 14 is provided; with this arrangement the neck member 14 is formed with an axial bore 23 for the accommodation of the spring 20, the cross bar 21 in such case lying between the one end of the neck member 14 and the internal flange 18, as shown in Fig. 2.

In Fig. 3 I have shown an arrangement adapted particularly for dolls having conventional soft bodies, the neck member 14^a in this case being upwardly tapering cylindrical form and extending into or being fitted in the neck socket 16^a with which the head 13^a is in this case also provided. As shown in the drawing, the neck member 14^a includes an outwardly projecting annular flange 24, preferably located at one end of said neck member 14^a. The latter is provided also with an axial bore 23^a which may, as shown, diverge upwardly and serves to accommodate the means whereby the neck member 14^a and the head 13^a are maintained in movable connection with each other; the means in question may consist as in the first form 25 of a rod 19, spring 20 and cross bar 21. In the finished doll the flexible body material 10^a which may be a suitable fabric or the like, projects over the flange 24 and is secured in place by a wire or other fastening means 30 25, which extends circumferentially about the neck member 14^a.

In the two forms so far described, the heads and the neck members, while they are constructed as separate independent member, are connected in the form of units adapted to be secured to the bodies 10 or 10^a, the neck members 14 and 14^a being fixed to said bodies and serving to adjustably or movably mount the heads thereon.

In the form shown in Fig. 5, the body 10^b is provided with a neck recess 16^b into which, in this case, one end of the neck member 14^b is movably seated, the outer end of said neck member 14^b being fitted in the neck socket 16^b with which the head 13^b is provided. With this arrangement the head is adjustable or movable on the neck member as in the previous forms, and in addition, the neck member 14^b is itself movable relatively 45 to the body 10^b, said neck member 14^b having its opposite ends rounded or curved to provide the necessary bearing surfaces to permit a large variety of relative movements of both the neck member 14^b and the head 50 55 13^b. The means whereby the head 13^b, neck member 14^b and body 10^b are maintained in movable connection with each other may be of any conventional form and as shown, consists of a rod 19^a, one end of which is embodied in the head 13^b, and the other end of which is connected with elastic cords or the like 26 which themselves may be attached to the legs of the doll for movably holding them 55 in proper position on the body 10^b in the well known way; in this form the neck mem-

ber 14^b is provided with an axial bore 23^b, through which the rod 19^a extends.

By constructing the neck member as a separate member independently of the body or head of the doll, the manufacture of the latter is facilitated and it is possible in the case of dolls having molded heads to simultaneously cast more head per given die than has heretofore been possible; experience has shown that the number of heads which may be molded with the present construction is as much as double that which is possible under existing conditions. In other words, by constructing the neck members as separate elements independently of the bodies and heads, instead of as integral parts of one or the other of these elements, the dimensions of the recesses in which the heads are cast may be materially reduced to compensate for the absence of the neck members to thereby increase the capacity of a given mold without in any way changing the dimensions thereof. At the same time, the novel arrangement hereinbefore described in all of its forms makes it possible to provide a common base with interchangeable heads so as to still further facilitate the production of the dolls and to reduce the cost thereof to a minimum. The novel construction applies with equal advantage to either soft or hard dolls, thus overcoming a disadvantage existing heretofore, which required one type of head for soft dolls and another type for hard or wood turned dolls.

With the construction shown in the drawings, the head is capable of any number of movements relatively to the body and in the form shown in Fig. 5, is capable of what may be termed "compound" movements, that is, movements of the head on the neck, and movements of the body and head relatively to the neck. The dolls made according to the invention may be made of any base material, excepting perhaps glass or metals, capable of receiving bonding agents, such as lacquer, cement, dextrin etc., varnish, casein, glue, etc. A flock may be applied to the surface covered with the bonding agent in sufficient quantities to cover the same so as to obtain the soft appearance in the doll which is very desirable. The doll may be tinted with stencils or the like in the usual manner to provide a very life-like appearance therein. The separate neck member has the further advantage that the doll in which it is incorporated is capable of yielding, this being particularly true of the form shown in Fig. 5. As a result of this, if the doll should be dropped either accidentally or intentionally the yielding action of the head and neck member within the body absorbs the impacts and thus reduces the possibility of breaking the doll to a minimum.

While any conventional type of means may be utilized for fastening the head and

neck member in movable connection with each other, or to correspondingly fasten the head, neck member and body together, it is preferred to utilize the novel means illustrated in the drawings for this purpose. Under such conditions the head 13 or its equivalent is cast or molded in two sections *a*, *b*, in each of which an undercut recess *c* is formed at the free edges thereof during the molding. The sections *a*, *b* are united with each other along the joint *d* by means of suitable glue, cement or the like, the recess *c* being so located as to register with each other at the joint *d* to form an internal seat having a reduced outlet *e* whereby shoulders *f* are formed, as shown in Fig. 6. Prior to the connection of the sections *a* and *b* with each other, the rod 19 or its equivalent has its one end placed in position in one of the recesses *c* so that said rod projects outwardly through the outlet *e* thereof. After the two sections *a* and *b* have been united in the manner hereinbefore described, the one end of said rod 19 will thus be embedded in the material of which the head is made. The aforesaid rod 19 may be provided with a head *g* sufficiently large to prevent its withdrawal through the outlet *e* or said rod may extend through a washer *h* of larger dimensions than the outlet *e*, in which case said washer is placed in position in the recess *c* before the sections *a*, *b*, are united with each other. In any case the one end of the rod 19 is firmly embedded in the head in engagement with the shoulders *f* which prevent unintentional disconnection of the rod 19 from the head under the tension imposed on said rod by the spring 20 or its equivalent. In addition to its other advantages, this arrangement of fastening means possesses the further advantage that it does not interfere with the tilting mechanism for the movable eyes if the latter are included in the doll in question. As shown in Fig. 3, the stem *i* carrying the counterweight *j* whereby the eyes *k* are adjusted in the sockets to give the effect of a sleeping doll, is bent so as to extend to one side of the rod 19 and its spring 20. The fastening arrangement in question is of extremely simple construction and of maximum efficiency for its intended purpose and presents no complications in the manufacture of the doll, but rather reduces the difficulties of such manufacture to a large extent. Furthermore, with the fastening means hereinbefore set forth, the necessity for fishing around within the head to make the required connections for the fastening means as is now the case, is entirely done away with.

Various changes in the specific form shown and described may be made within the scope of the claim without departing from the spirit of the invention.

65 I claim:—

In a doll, a body, a hollow head consisting of two sections joined together along a predetermined line, the walls of the two sections having opposed recesses in their meeting faces, the portions of the meeting faces of the walls between said recesses and the outer side of the walls being in contact, said walls having restricted openings in the portions of the meeting faces between the recesses and the inner side of the walls connecting with said recesses, whereby said recesses and said openings form a seat closed on the outer side of the head and opening through a restricted portion into the inner side of the head, a rod extending at one end through said restricted opening into said seat, an enlarged portion on said end seated in said seat, the said rod extending into the hollow of the head, and means connected to said rod and to the body for holding the head on the body.
